UNITED STATES PATENT OFFICE.

NELS A. LEREN, OF MINNEAPOLIS, MINNESOTA.

COUNTERBALANCING DEVICE FOR WINDOW SASHES.

Application filed November 21, 1925. Serial No. 70,501.

This invention relates to counter-balanced window sashes and especially to that type of counter-balanced sashes wherein the upper and lower sashes are connected by means of flexible members passed over pulleys or guide members carried at the top of the window frame.

It is the main object of this invention to provide an extremely simple but highly efficient counter-balancing device for slideable sashes which will not only permit said sashes to be held in various opened positions but will, moreover, permit one of said sashes to be opened for some distance while the other sash is closed. It is often desirable in a room, in order to avoid a draught, to open only the lower sash, which function is impossible with most counter-balancing devices now on the market.

It is a further object of the invention to provide means, in combination with a lock adapted to secure the lower sash to the window frame in various raised positions, which will permit the connection between the ends of the flexible members employed and the sashes to yieldingly give, whereby the lower sash may be opened to a desired position and locked with the other sash closed.

A more specific object of the invention is to provide the sashes with vertically disposed seats or grooves in the sides thereof wherein the ends of the flexible members or connecting members are disposed and to interpose between the extremities of said connecting members and the upper ends of said seats, resilient members adapted to perform the functions above set forth. Said resilient members are preferably in the form of springs coiled about tubular members or rods connected to the flexible members themselves.

It is a still further object to provide means for adjusting the tension on said springs and means also for preventing the further compression thereof beyond certain limits.

These and other objects of the invention will be apparent from the following description made in connection with the accompanying drawings, wherein like characters refer to similar parts throughout the several views, and in which,

Fig. 1 is a fragmentary front elevation of an embodiment of the invention applied to the usual window frame with the lower sash closed and the springs tensioned, some portions being broken away and others shown in section;

Fig. 2 is a vertical section of the same on a larger scale taken on the line 2—2 of Fig. 1;

Fig. 3 is a fragmentary view, similar to Fig. 2, on a larger scale showing the sash in normal counter-balanced position with the spring untensioned;

Fig. 4 is a horizontal cross section taken on the line 4—4 of Fig. 1; and

Fig. 5 is a detailed view showing a modified form of the flexible member and spring construction.

In the drawings a window frame of the usual type, indicated by the numeral 6, is provided at either side thereof with the usual sash guides 7 and at the top with the sash guides 7^a connecting therewith. The upper sash 8 and the lower sash 9 are of standard type, dove-tailing at their intersecting surfaces adjacent the horizontal middle of the window frame. In each side of sashes 8 and 9 longitudinal vertically disposed seats or grooves 8^a and 9^a, respectively, are formed at the outer edges, extending from the top of the sash downwardly to points adjacent the bottom of the sash. In the lower sash 9 the seats 9^a communicate with preferably cylindrical seats of larger diameter 9^b extending from points adjacent the bottom of sash 9 to points approximately one-third of the height of said sash, forming the annular flanges or shoulders 9^c at the plane of intersection with seats 9^a. Fixed sleeves 10 are provided, fitting snugly within the top portions of each of the seats 8^a and 9^a respectively of the sashes 8 and 9 and adjustably secured thereto by means of set screws 11 extending from the room side of the respective sashes into contact with the sleeves 10. A pair of transversely disposed pulleys 12 are rigidly secured to the top board of window frame 6, each substantially in alignment with the seats 8^a and 9^a on one side of the sashes.

A flexible member 13 is passed over each of pulleys 12, the ends thereof depending and approximately aligned with the seats 8^a and 9^a in the upper and lower sashes at that side of the window frame. The ends of each of the flexible members 13 are passed through the fixed sleeves 10 in the respective sashes and connected in any suitable manner to relatively small rods or tubular members 14 slidably disposed in sleeves 10.

In the drawings members 14 are shown as hollow and the connection between the flexible members and said tubular members are

made by passing the ends of flexible members 13 through the members and knotting the extremities of the flexible members, interposing a contacting member or washer 15 between the knots and the lower ends of the members 14. Upper sash 8 is thus connected to lower sash 9 over pulleys 12 for counter-balancing.

Coiled springs X surround tubular members or rods 14, having their ends interposed between the lower ends of fixed sleeve members 10 and washers or contacting member 15. The springs X on the upper sash may be dispensed with and a positive connection made between the ends of flexible members 13 and the tubular members or rods 14. However, if springs x are used as illustrated the same are tensioned considerably less than the springs X employed 20 in the lower sash, the purpose of which will later be set forth.

Both upper and lower sashes 8 and 9 at one side of the window frame preferably have rack plates 16 secured to the outer edges thereof covering seats 8^a and 9^a, respectively, and a window lock or ventilation lock of any suitable type which will lock the lower sash against further opening in a desired closed or opened position is mounted 30 at one side of window frame 6 adapted to engage the several teeth or holes in plate 16. An ordinary window lock securing the sashes together at their overlapping portions may, of course, be used but will not permit 35 the sashes to be locked in a variety of different opened positions. Preferably the lock 18 employed, corresponds to the device disclosed and described in applicant's pending application for patent entitled "Ventilation locks for window sashes," filed January 13, 1923, S. N. 612,376. This form of lock 40 may be quickly manipulated from the room side of the window frame by a single pull rod 18^a which is adapted to release dogs or bolts 19 to permit engagement thereof with the rack plates on the side edges of the sash.

Knots 13^a, or the equivalent thereof, are made in the flexible members 13 above the top of the sleeves 10 in upper sash 8, operative to prevent tension from being placed 50 on springs X in the upper sash when the sashes are in closed position. These knots, as shown in Figs. 1 and 2, are adapted to abut against the top of the window frame 55 6 through which the flexible member is passed.

In smaller sash, or, if desired, in larger sash, the rods or tubular members 14 may be omitted as well as sleeve members 10 and 60 the coiled springs X will embrace the cords or flexible members 13 themselves. However, as shown in Fig. 5, if these parts are omitted, it is found highly efficient to dip 65 the end portions of the flexible members 85 normally disposed within seats 8^a and 9^a,

into lacquer or some other self-hardening material which will stiffen the ends and leave a smooth substantially cylindrical surface on the outer sides thereof for the springs to work over. The springs X may 70 then be interposed between the usual washers 15 and a plate or washer 17 rigidly secured in the intermediate portion of seats or recesses 8^a and 9^a.

Operation.

75

Assuming the sashes to be in normal closed position with the lock 18 securely holding the sashes locked, considerable tension will be placed upon the springs X with- 80 in lower sash 9, as shown in Figs. 1 and 2. When the rod 18^a is pulled, the sashes will be released and the tension of springs X on the lower sash will cause the lower sash 9 to automatically be raised on rods or tubular members 14 to the position shown by the dotted lines in Fig. 1. There will be no tension on springs X of the upper sash 8 since the knots 13^a in flexible members 13 contact the upper surface of window frame 90 6. Thus, the lower sash 9 may be automatically raised without lowering upper sash 8 merely by releasing the lock 18. If, of course, it is desired to open both sashes, lower sash 9 may be further raised, where- 95 upon upper sash 8 will drop accordingly and said sashes 8 and 9 will be counter-balanced in a desired opened position.

When it is desired to close both sashes, lower sash 9 is simply depressed, thereby 100 elevating upper sash 8 to closed position and the lock 18 is put on by depressing the pull rod 18^a. If the form of ventilation lock described in the above identified pending application of inventor's is employed, 105 the same may be set before sash 9 is lowered, whereby the lower sash may be depressed and left at any desired position or may be closed entirely and held closed by said lock.

While it is contemplated by the inventor 110 that the springs X are not necessary in the upper sash 8, it is found that, by employing springs and tensioning the same very 115 slightly, in combination with the lock hitherto described, the weight of the upper sash will be sufficient to permit the same to be opened to some extent without opening lower sash 9 because of the frictional engagement with said ventilation lock em- 120 ployed.

The tension on springs X may be obviously 125 regulated by loosening the set screw 11 and adjusting the relative longitudinal position of sleeves 10 to the sash in which mounted, if desired. By so doing, the upper seat for the spring is varied, which, of course, varies the tension.

In the lower sash the shoulders 9^c afforded by the intersection of seat 9^b with seat 9^a, 130 provide a stop or abutment for washer 15,

thereby positively connecting flexible member 13 with said lower sash 9 when springs X have been sufficiently compressed to permit said shoulders and washer to be mutually engaged. Thus, provision is made to prevent undue strain on the springs employed, thereby insuring the same against breakage.

The applicant has put his invention to considerable actual usage and has found the same highly efficient for all the purposes intended.

It will be seen from the above description that the applicant has invented a simple but efficient counter-balancing device for sliding window sashes, capable of wide general usage, inexpensive to manufacture and permitting the sashes on which employed to not only be counter-balanced in desired opened positions but permitting one of the sashes to be opened to some extent while the other sash is closed.

It will, of course, be understood that various changes may be made in the form, details, proportions and arrangement of parts without departing from the scope of the invention.

What is claimed is:

1. In combination with a window frame and upper and lower sliding sashes therefor, counter-balancing mechanism having in combination a guide member at the top of said window frame, a flexible member secured at one end to said upper sash and passed over said guide member, said lower sash having a vertical seat in a side thereof, the other end of said flexible member extending into said seat, a tubular member about the lower end of said flexible member slidable in said seat, a contacting member secured to the lower extremity of said flexible member below said tubular member, and a coiled spring on said tubular member interposed between said contacting member and the upper end of said seat, and a lock for holding said lower sash in a plurality of positions relative to the side of said window frame.

2. In combination with a window frame and upper and lower sliding sashes therefor, counter-balancing mechanism having in combination guides carried at either side thereof, said sashes having vertically disposed seats in the sides thereof, flexible members one at each side of said frame mounted over said guides, each having their ends disposed in the seats of said sashes at one side of said window frame, elastic members disposed in said seats and interposed between the extremities of said flexible members and the upper ends of said seats, and means for locking said lower sash in various raised positions.

3. A counter-balancing device for slidable window sashes having in combination a guide adapted to be supported from the top of a

window frame, a flexible member secured to one of said sashes and passed over said guide, a vertically slidable member mounted in the other of said sashes having its upper end connected to the other end of said flexible member, resilient means compressible between the lower end of said slidable member and a seat in said sash, and means for locking said sashes in closed position.

4. The structure set forth in claim 3, and means for limiting the compression of said resilient member.

5. A counterbalancing device for sliding window sashes having in combination a guide adapted to be supported from the top of the window frame, a flexible member having one of its ends connected to one of said sashes and passed over said guide, the other end of said flexible member extending substantially vertically into said other sash, an elongated elastic element within said last mentioned sash connecting said last mentioned end of said flexible member therewith to render the length of said flexible member between said sashes adjustable, means for maintaining said last mentioned end of said flexible member within said last mentioned sash with freedom for slidable movement and means for locking said sashes in closed position with said elastic element tensioned.

6. In combination with a window frame, upper and lower vertical sliding sashes, counterbalancing mechanism having in combination, a guide supported from the top of said window frame, a flexible member passed over said guide and having one end connected to one of said sashes, said other sash having a substantially vertical recessed portion for receiving said flexible member, an elastic element disposed within said recessed portion connecting the other end of said flexible member with said sash to render the length of said flexible member between said sashes adjustable, means for maintaining said last mentioned end of said flexible member within said sash with freedom at all times for slidable movement therein against the tension of said spring and means for locking said sashes in closed position.

7. In combination with a window frame, upper and lower vertical sliding sashes, counterbalancing mechanism having in combination, a guide supported from the top of said window frame, a flexible member passed over said guide and having one end connected to one of said sashes, said other sash having a substantially vertical recessed portion adapted to receive the other end of said flexible member, a seat medially disposed in said recessed portion, a coiled spring surrounding said last mentioned end of said flexible member and interposed for compression between the extremity thereof and said seat to render the length of said

- flexible member between said sashes adjustable, means for maintaining said flexible member within said recessed portion with freedom at all times for slidable movement
5 against the tension of said spring and means for locking said sashes to said window frame in a plurality of different positions.
8. In combination with a window frame, upper and lower vertical sliding sashes,
10 counterbalancing mechanism having in combination a guide supported from the top of said window frame, a flexible member passed over said guide and having one end connected to one of said sashes, said other sash having a substantially vertical elongated recessed portion in one side thereof adapted to receive the other end of said flexible member, a spring seat medially disposed in said

recessed portion, a stop member adjacent the extremity of said last mentioned end of 20 said flexible member and disposed within said recessed portion, a coiled spring surrounding said flexible member and interposed between said spring seat and said stop member, said flexible member being 25 mounted with freedom for slidable movement in said recessed portion against the tension of said spring, a shoulder in said recessed portion below said spring seat adapted to be engaged by said stop member 30 to limit the slidable movement of said flexible member and means for locking said sashes to said window frame in a plurality of different positions.

In testimony whereof I affix my signature.
NELS A. LEREN.
